[57] ABSTRACT

An active diode circuit in which two matched pairs of transistors are connected together in the output circuit of an operational amplifier in such a manner as to provide a positive-going half-wave rectified output signal, a negative-going half-wave rectified output signal and an unrectified output signal. More particularly, a first NPN transistor and a first PNP transistor are interconnected between a first output terminal and the output of the operational amplifier in such a manner as to duplicate the amplifier output at the first output terminal; a second NPN transistor is connected in parallel with the first NPN transistor in such a manner as to develop the positive-going rectified output signal at a second output terminal; and the second PNP transistor is connected in parallel with the first PNP transistor in such a manner as to develop the negative-going rectified output signal at a third output terminal.

IMPROVED RECTIFYING CIRCUIT BACKGROUND OF THE INVENTION

1. Field of the Invention

The present invention relates generally to electronic rectifying devices and more particularly to an active diode circuit wherein matched pairs of bipolar transistors are utilized in conjunction with an operational amplifier to provide a triple output rectifying circuit having voltage swings substantially larger than heretofore available in prior art.

2. Description of the Prior Art

In theory, a diode is a device which conducts current in only one direction and while in the conductive state has input and output voltages which are essentially equal. When the diode is biased in the reverse direction, that is, in the direction which would tend to make the current flow in the direction opposite to the conductive direction, there will be no conduction.

In practice however, the diodes do have a forward voltage drop which is significant in the operation of many systems utilizing such rectifying devices. In such cases, it is usual to resort to the use of an active diode circuit wherein several discrete diodes are connected to an operational amplifier in such a manner that the total operational effect of the circuit is as though an ideal diode were incorporated. However, the disadvantage of this type of approach is that the total output voltage available is still no greater than the supply voltage minus the forward voltage drop across the output diode (about $\frac{1}{2}$ volt) and the internal limitations of the operational amplifier.

Using the active diode configuration, the op-amp circuit is typically capable of swinging within 1 volt of the supply. Adding this 1 volt drop to the $\frac{1}{2}$ volt diode drop means that the maximum available voltage will be $1\frac{1}{2}$ volts less than the supply voltage. Although the loss of the $1\frac{1}{2}$ volts may be inconsequential in many applications, it is of substantial consequence in certain automotive applications and the like wherein the voltage supply is low at the outset. For example, in fuel injection applications which must operate when the battery is low and the engine is being started at low temperatures, the typical supply voltage is only 6 volts and the loss of $1\frac{1}{2}$ volts on each end will be quite serious.

SUMMARY OF THE PRESENT INVENTION

It is therefore a principle objective of the present invention to provide an active diode circuit in which the prior art output swing limitations are substantially improved.

Another objective of the present invention is to provide an active diode circuit for accomplishing the above stated objective using monolithic integrated circuit technology.

Briefly, the present invention includes an operational amplifier combined with two PNP transistors and two NPN transistors in such a manner as to provide one output signal for the positive going portion of an input signal, one output signal for the negative going portion of an input signal, and a third output signal which corresponds to both positive and negative going portions of the input signal. More particularly, one of the NPN transistors and one of the PNP transistors are interconnected between a first output terminal and the op-amp output in such a manner as to duplicate the op-amp output at the first output terminal, the second NPN transistor is connected in parallel with the first NPN

transistor to develop a rectified output of one polarity and a second output terminal, and the second PNP transistor is connected in parallel with the first PNP transistor and is operative to develop a rectified output of the opposite polarity at a third output terminal.

Among the advantages of the present invention is that it provides an active diode device and is capable of developing three separate output signals, two of which are rectified signals of opposite polarity and a third output signal which is a composite of the other two with each swinging within one volt of the supply voltage.

Other objects and advantages of the present invention will no doubt become apparent to those of ordinary skill in the art after having read the following detailed description of the preferred embodiments which are illustrated in the several figures of the drawing.

IN THE DRAWING

20 FIG. 1 is a simplified schematic diagram illustrating an active diode circuit in accordance with the present invention;

15 FIG. 2 is a schematic diagram illustrating a pre-biasing circuit for use in accordance with the circuit illustrated in FIG. 1;

25 FIG. 3 is a diagram illustrating a transfer characteristic of the circuit shown in FIG. 1;

30 FIG. 4 is a diagram illustrating the transfer characteristic of an active diode circuit of the type shown in FIG. 1 modified to include the pre-biasing circuit shown in FIG. 2; and

35 FIG. 5 is a detailed schematic representative of an actual embodiment of an integrated circuit version of an active diode circuit in accordance with the present invention.

DETAILED DESCRIPTION OF THE PREFERRED EMBODIMENT

40 Referring now to FIG. 1 of the drawing, a simplified embodiment of an active diode circuit in accordance with the present invention is shown. The circuit is generally comprised of an operational amplifier 10, an active rectifying circuit 11, and various input, output and power supply terminals as shown. Op-amp 10 includes an inverting input 12, a non-inverting input 14 and an output 16. A positive source of potential $V^{+}115$ is applied at 18 and a negative source of potential V^{-} is applied at 20. Op-amp input 12 is coupled to the circuit input terminal 23 through an input resistor R_1 and is connected to a circuit output terminal 22 by a feedback resistor R_2 as will be explained in more detail below. The non-inverting input 14 is coupled to circuit ground at 15 through an equivalent resistor R_{eq} which is selected to have a resistive value equal to the parallel resistive values resistors R_1 and R_2 . R_{eq} compensates for the input bias current and causes the non-rectified output of the circuit to be equal to $-V_{in}(R_2/R_1)$.

45 The rectifying circuit 11 is connected between the output 16 of op-amp 10 and the three output terminals 22, 24, and 26 and includes four transistors Q_1 , Q_2 , Q_3 and Q_4 . Transistor Q_1 is an NPN transistor having its base b_1 connected to op-amp output 16, its collector c_1 connected to the voltage supply V^{+} , and its emitter e_1 connected to output terminal 22. Transistor Q_2 is a PNP transistor having its base b_2 connected to op-amp output 16, its collector c_2 connected to the negative power supply V^{-} , and its emitter e_2 connected to output

terminal 22. Transistor Q_3 is an NPN transistor having its base b_3 connected to op-amp output 16, its collector c_3 connected to the positive power supply V^+ , and its emitter e_3 connected to output terminal 26. Transistor Q_4 is a PNP device having its base b_4 connected to op-amp output 16, its collector c_4 connected to the negative power supply V^- , and its emitter e_4 connected to output terminal 24.

The output voltages V_1 , V_2 and V_3 are taken across load resistors R_{L1} , R_{L2} and R_{L3} respectively at terminals 22, 24 and 26. As indicated previously, feedback for the circuit is accomplished by means of a circuit including resistor R_2 which is connected between output terminal 22 and the inverting input 12 of op-amp 10. Although the transistors Q_1 - Q_4 may be discrete elements carefully selected to have matched operational parameters over a particular temperature range, in the preferred embodiment these elements are integrated circuit devices having equal base, emitter and collector elemental areas formed in a common semiconductor chip including the op-amp 10. As a result, transistors Q_1 and Q_3 are identical and experience identical current flows, and transistors Q_2 and Q_4 are likewise identical and experience equal current flows so long as the respective load currents are the same. Good thermal coupling within the monolithic structure aids in this matching.

In operation, for a given input signal V_{in} applied to input terminal 23, an amplified signal will be developed at the op-amp output 16 which will tend to either forward bias or reverse bias the transistors Q_1 - Q_4 depending upon whether the voltage is positive or negative. For positive voltages developed at 16, the base-to-emitter junctions of transistors Q_1 and Q_3 will be forward biased causing Q_1 and Q_3 to conduct as soon as the base-to-emitter potentials exceed $1V_{BE}$. Similarly, for negative voltages developed at op-amp output 16, transistors Q_2 and Q_4 will be forward biased, causing Q_2 and Q_4 to conduct as soon as the base-to-emitter potential exceeds $1V_{BE}$. Accordingly, for positive-going outputs, the voltage at terminal 26 may be expressed generally as (1)

$$V_3 = V_1 + V_{OS1-3}$$

and for negative going outputs the voltage output at terminal 24 may be expressed as (2)

$$V_2 = V_1 + V_{OS2-4}$$

where

V_{OS1-3} and V_{OS2-4} are the offset voltage errors caused by imperfect matching between the transistors indicated by the subscript. In both cases the output voltage V_1 may be expressed as

$$V_1 = -V_{in}(R_2/R_1) + V_{OS}(1R_2/R_1) \quad (3)$$

where

V_{OS} is the input offset voltage of the op-amp 10.

In their more complex forms the output voltages V_2 and V_3 may respectively be expressed as

$$V_2 = -V_{in}(R_2/R_1) + V_{OS}(1+R_2/R_1) + V_{OS2-4} \quad V_{in} < 0 \quad (4)$$

$$V_3 = -V_{in}(R_2/R_1) + V_{OS}(1+R_2/R_1) + V_{OS1-3} \quad V_{in} > 0 \quad (5)$$

Conduction of transistors Q_3 and Q_4 in the modes opposite to those discussed above is dependent upon the design of the output stage including transistors Q_1 and Q_2 . Ideally, as voltage V_1 falls, transistor Q_1 should conduct progressively less until $V_1 = 0$, then the current I_{Q1} should equal I_{Q2} should equal 0. As voltage V_1 falls below 0 potential, transistor Q_1 should cease to con-

duct and all of the load current should be carried by transistor Q_2 . In practice however, transistor Q_1 and Q_2 will either have a deadband as illustrated or will be pre-biased so that their conductive phases overlap.

In the case of deadband operation, transistor Q_1 will conduct for all positive output voltages. When $V_1 = 0$ $^+$ transistor Q_1 will reach 0 current and transistor Q_2 will still be biased OFF. Voltage V_3 will be equal to a fraction of V_{OS1-3} and V_2 will be 0. A small positive change in V_{in} will cause the drive of transistors Q_1 and Q_2 to change at a rate set by the open loop gain and slew rate until transistor Q_1 is reverse biased and transistor Q_2 is on the verge of conduction. Then voltage V_3 will be 0 and voltage V_2 will be equal to a fraction of V_{OS2-4} . The amount of input voltage change required to achieve this switching is

$$\Delta V_{in} = 2V_D/A_{VOL} \quad (6)$$

where

$2V_D$ is the deadband voltage between the swings of Q_1 and Q_2 and

A_{VOL} is the open loop voltage gain of the op-amp 10. In the illustration, $2V_D$ is approximately equal to $2V_{be}$.

For an open loop voltage gain of 80db and a deadband voltage of 1V, the equivalent input deadband voltage is 0.1mV. For negative values of V_1 , transistor Q_3 will be reverse biased and voltage V_3 will be 0 except when V_1 is more than $(V_{BE}+BV_{EBO})$ below ground where BV_{EBO} is the emitter-base breakdown voltage. In the latter condition, V_3 will follow V_1 as transistor Q_3 is forced to conduct in the reverse breakdown mode. In applications where the supply voltage is less than $2(V_{BE}+BV_{EBO})$ this phenomenon will not be experienced.

The total effective offset of the device is a function of both input and output offset voltages and the offset voltages can be adjusted by trimming the three load resistors R_L . It may be possible to use the technique to take care of both input and output offset voltages.

Although it may be undesirable for some applications to have both Q_1 and Q_2 conducting simultaneously as this will cause unwanted outputs V_2 and V_3 , a pre-biasing circuit such as that illustrated at 28 in FIG. 2 may be incorporated into the circuit shown in FIG. 1. Although many circuit configurations could be utilized, the basic circuit illustrated includes a single NPN transistor Q_B and a pair of biasing resistors R_{B1} and R_{B2} . R_{B1} is connected between the base and collector of Q_B , and R_{B2} is connected between the base and emitter. In incorporating the bias circuit 28 into the circuit of FIG. 1, terminal 17 is connected to op-amp output 16, the collector Q_B , terminal 27, is connected to the base b_1 of Q_1 , and the emitter of Q_B , terminal 29, is connected to the base b_2 of Q_2 .

The effect of the two resistors R_{B1} and R_{B2} is to multiply the emitter-base potential of Q_B by $(1 + R_{B1}/R_{B2})V_{BE}$.

Referring now to FIG. 5 of the drawing, a more detailed schematic diagram of a complete active diode circuit suitable for integrated circuit applications is illustrated. Like callout numbers and letters in FIGS. 1 and 5 refer to corresponding elements. The operational amplifier portion of the circuit is shown enclosed in the dashed lines 10 and is comprised of a biasing section 30, a first amplifying stage 32 and a second amplifying stage 34. The biasing portion 30 includes three PNP

transistor devices Q₆, Q₇ and Q₈, two NPN transistors Q₉ and Q₁₀, and four resistor elements R₆, R₇, R₈ and R₉ connected together as illustrated in the drawing. This section is operative to provide appropriate biasing levels to the amplifying stages 32 and 34.

Amplifying stage 32 is comprised of four PNP transistors Q₁₁, Q₁₂, Q₁₅ and Q₁₆, four NPN transistors Q₁₃, Q₁₄, Q₁₇ and Q₁₈, and four resistor elements R₁₀, R₁₁, R₁₂ and R₁₃. This stage includes a differential input to the bases of transistors Q₁₃ and Q₁₄ through resistors R_{eq} and R₁ respectively (input terminals 15 and 23), and a single-ended output at circuit node 40. Transistors Q₁₁ and Q₁₂ provide additional biasing for the stage while transistors Q₁₅ and Q₁₆ provide common mode feedback for setting the bias level of the output stage in such a way that it is independent of variations in PNP beta. Transistor Q₁₇ reflects the input current into the transistor Q₁₈ so that there is no gain loss as would be the case if the collector Q₁₆ were coupled to ground.

In the second stage 34, transistor Q₂₁ is an emitter follower having its base coupled to the output 40 of the first stage and provides current gain but no voltage gain. Transistor Q₂₂ is a level shifting device which brings the voltage down again to the base potential of transistor Q₂₄. Transistor Q₂₄ is a common emitter amplifier having a very high gain. Transistors Q₁₉ and Q₂₀ provide bias for the second stage, and the transistor Q₂₃ acts as a current source for the level shifter Q₂₂. Frequency response compensation is provided by capacitor C₁ which feeds back a signal from the output of the second stage to the input of that stage in a conventional manner.

In addition to the four output elements Q₁, Q₂, Q₃ and Q₄, this circuit also includes a pre-biasing circuit 28 which includes the transistor Q₅ and a pair of resistors R₁₆ and R₁₇ which are connected in series between the collectors of transistors Q₂₀ and Q₂₄. The base b₅ of transistor Q₅ is connected to the junction of R₁₆ and R₁₇, the collector c₅ is connected to the base of transistor Q₁, and the emitter e₅ is connected to the base of transistor Q₂. Resistors R₁₆ and R₁₇ serve as a V_{BE} multiplier as previously described. The operation of the circuit is limited in the positive direction by the saturation voltage of Q₂₀ and in the negative direction by the saturation voltage of Q₂₄. The pre-biasing circuit provides partial bias to Q₁ and Q₂ so that the voltage of the circuit node 52 does not have to swing two V_{BE} to commute the conductance from Q₁ to Q₂, i.e., it only has to go through a fraction of the V_{BE} as set by the resistors R₁₆ and R₁₇ and that fraction of V_{BE} is the deadband shown in the transfer characteristic.

When the output 22 is positive with respect to the load, Q₃ is conductive and Q₂ is non-conductive. When Q₁ is conductive Q₃ will also be conductive. And since Q₂ is non-conductive, Q₄ will also be non-conductive so that the output at terminal 22 is positive and the output at terminal 24 is 0. The pre-bias provided by transistor Q₅ assures that Q₁ and Q₂ do not conduct at the same time since maximum differential voltage between their bases can only be equal to one diode drop which is that across the emitter base junction of transistor Q₅.

When loads-to-ground are coupled to the emitters of transistors Q₃ and Q₄, current will flow from either of the two transistors depending upon the state of the input signal. If equal loads are applied in the outputs of Q₃ and Q₄, for example, if Q₁ is conducting, Q₃ will have the same base potential and have equal emitter

current. When the output reaches the load reference voltage, Q₁ will cut OFF and so will Q₃. Q₂ and Q₄ will then turn ON and will carry equal currents. Therefore, the output from the emitter of Q₄ will be a replica of the negative-going portion of the output voltage on the common point between Q₁ and Q₂, i.e., output terminal 22, whereas the output developed at the emitter of Q₃ will be a replica of the positive-going portion of this signal. This circuit has the advantage that the output swing available from the rectified outputs (terminals 24 and 26) is equal to the output swing that is available from the normal amplified output at terminal 22.

Whereas the conventional active diode connection requires an additional diode connected externally from the regular output of the amplifier so that the total output swing is reduced by an amount equal to one emitter base drop which is on the order of 0.6V. The present invention is of particular advantage when the system is designed to operate with a low supply voltage and provides the additional advantage that both positive-going and negative-going diode effects are achieved simultaneously with one circuit and that these are matched in output capability to the output of the operational amplifier. If desired, all three outputs may be connected together and the device may operate as a conventional amplifier. However, in this mode there will be some cross-over distortion due to the biasing provided by Q₅.

Although the present invention has been described in terms of preferred embodiments which are described above for purposes of illustration, it is contemplated that other alterations and modifications will become apparent to those of ordinary skill in the art. Accordingly, the appended claims are to be interpreted as covering all such alterations and modifications as fall within the true spirit and scope of the invention.

What is claimed is:

1. A rectifying circuit having first, second, and third output terminals comprising:
  - a. operational amplifying means responsive to an input signal and operative to develop an amplified signal commensurate therewith, which includes an inverting input terminal, and a feedback circuit coupled between said inverting input terminal and the first output terminal;
  - b. a first NPN transistor having a base element coupled to the output of said operational amplifying means, a collector element for connection to a power supply of positive potential and an emitter element connected to the first output terminal;
  - c. a first PNP transistor having a base element coupled to the output of said operational amplifying means, a collector element for connection to a power supply of negative potential, and an emitter element connected to the first output terminal, said first NPN transistor and said first PNP transistor being operative to develop a non-rectified output signal at the first output terminal corresponding to said amplified signal;
  - d. a second NPN transistor having a base element coupled to the output of said operational amplifying means, a collector element for connection to said power supply of positive potential and an emitter element connected to the second output terminal, said second NPN transistor being operative to develop a first rectified output signal corresponding to positive-going polarities of said signal;

- e. a second PNP transistor having a base element coupled to the output of said operational amplifying means, a collector element for connection to said power supply of negative potential and an emitter element connected to said third output terminal, said second PNP transistor being operative to develop a second rectified output signal corresponding to negative-going polarities of said amplified signal; and
  - f. a pre-biasing circuit means including a third NPN transistor having a base element coupled to the output of said operational amplifying means, a collector element connected to the base of said first NPN transistor and an emitter element connected to the base of said first PNP transistor.
2. A rectifying circuit as recited in claim 1 wherein said pre-biasing circuit means further includes a first biasing resistor connected between the base and collector elements of said third NPN transistor, and a second biasing resistor connected between the base and emitter elements of said third NPN transistor.

3. A rectifying circuit having first second and third output terminals, comprising:

- an operational amplifier having an inverting input terminal, a non-inverting input terminal and an amplifier output terminal;
- a first bipolar transistor having a base element coupled to said amplifier output terminal, a collector element for connection to a power supply of positive potential and an emitter element coupled to said first output terminal;
- a second bipolar transistor having a base element coupled to said amplifier output terminal, a collector element for connection to a power supply of negative potential and an emitter element coupled

5 to said first output terminal;

a third bipolar transistor having a base element coupled to said amplifier output terminal, a collector element for connection to the collector element of said first bipolar transistor and an emitter element coupled to said second output terminal;

a fourth bipolar transistor having a base element coupled to said amplifier output terminal, a collector element coupled to the collector element of said second bipolar transistor and an emitter element coupled to said third output terminal; and

a feedback circuit coupling said first output terminal to said inverting input of said operational amplifier, whereby a positive-going voltage applied to said inverting input terminal causes a negative-going output voltage to be developed on said first and third output terminals, and a negative-going voltage applied to said inverting input causes a positive-going output voltage to be developed on said first and second output terminals.

4. A rectifying circuit as recited in claim 3 wherein said first and third bipolar transistors are NPN devices and said second and fourth bipolar transistors are PNP devices.

25 5. A rectifying circuit as recited in claim 4 and further comprising a pre-biasing circuit including a fifth bipolar transistor having a base element coupled to said amplifier output terminal, a collector element coupled to the base element of said first bipolar transistor, and an emitter element coupled to the base element of said second bipolar transistor, whereby said fifth bipolar transistor causes said first bipolar transistor and said second bipolar transistor to be conductive for different operational amplifier output voltages.
